UNITED STATES PATENT OFFICE.

WILLIAM E. NICKERSON, OF CAMBRIDGE, MASSACHUSETTS, ASSIGNOR TO GILLETTE SAFETY RAZOR COMPANY, OF BOSTON, MASSACHUSETTS, A CORPORATION OF DELAWARE.

BLADE-HANDLING APPARATUS.

1,255,917.

Specification of Letters Patent. Patented Feb. 12, 1918.

Application filed May 20, 1916. Serial No. 98,932.

To all whom it may concern:

Be it known that I, WILLIAM E. NICKERSON, a citizen of the United States, residing at Cambridge, in the county of Middlesex and State of Massachusetts, have invented certain new and useful Improvements in Blade-Handling Apparatus, of which the following is a specification.

This invention relates to a blade-handling mechanism by means of which safety razor blades may be taken one by one from a source of supply, transferred to and deposited in a blade holder preparatory to being sharpened or otherwise acted upon, and subsequently removed from the blade holder and delivered at a predetermined point. The specific embodiment of my invention herein-after described, which is pneumatically-operated, is designed to handle thin, double-edged blades such as are used in the Gillette safety razor, and is particularly adapted and intended for use in connection with blade-stropping devices and a pneumatically-operated blade holder of the character shown and described in co-pending applications for U. S. Letters Patent, Serial Nos. 49,164 and 75,794, the result of the conjoint use of these blade-stropping, blade-holding and blade-manipulating mechanisms being that a complete blade-stropping machine is provided which may be rendered fully automatic in its action by suitably controlling the pneumatic connections. The principal features of the invention reside in the arrangement employed for supporting supply and delivery stacks of blades and shifting their position, in the blade-transferring device which co-operates with said stack support, and in the means for operating these parts.

In the accompanying drawings, which illustrate my blade-handling mechanism as preferably constructed for the specific purpose above referred to,

Figure 1 shows the assembled parts mainly in side elevation, but with certain portions broken away;

Fig. 2 is a partial front elevation;

Fig. 3 is a central vertical section on a larger scale, illustrating the parts which transfer the blades to and from the blade holder;

Fig. 4 shows the bottom face of a suction block hereinafter described;

Fig. 5 is a top view of said block;

Fig. 6 is a perspective view showing a sleeve forming a part of the blade-transferring mechanism;

Fig. 7 is a similar view showing the suction block combined with the parts which carry it;

Fig. 8 is mainly a central, vertical section on a larger scale, illustrating the support for the blade stacks and its operating mechanism; and

Fig. 9 is a sectional plan view on the plane indicated by the line $\alpha-\alpha$ in Fig. 8.

The working parts of the apparatus illustrated are supported by a base plate 2 which also carries the blade holder to and from which the blades are transferred one by one and in which they are held while being stopped. This blade holder is located at the front of the machine, which is shown at the left hand end of Fig. 1, and comprises a carriage 3 movable laterally on the top surface of a bracket 4 bolted to the base plate 2, an upright pedestal 5 secured to the top of the carriage 3, and a blade-clamping device secured to the top of the pedestal 5 and including a fixed jaw 6 having a horizontal top surface for supporting a blade and an upper jaw 7 hinged thereto and provided with springs 8 which automatically lift it to a vertical position, as shown in Fig. 2, whenever such movement is permitted. The fixed jaw 6 on which the blades are successively deposited is provided with a pair of upwardly extending pins 9 spaced to enter the end perforations in a Gillette blade and position the same with respect to the jaws, the upper jaw 7 being provided with corresponding perforations 10 which receive the upper ends of the pins 9 when the jaws are closed. Means are also provided for closing the jaw 7 and holding it in closed position, and for moving the blade holder laterally toward and away from the stropping device (not shown), which in the complete machine are carried by the base plate 2 and located at a short distance to the left of the blade holder when the latter occupies the position shown in Fig. 2, in which it is at the limit of its movement away from said stropping devices. The means employed for closing the jaw 7 and for moving the blade holder laterally are not illustrated herein,

but for present purposes it may be assumed that these parts are operated pneumatically as explained in my co-pending application 110

Serial No. 75,794, above referred to, which shows a blade holder identical in construction with that herein illustrated.

The blades to be operated upon are introduced into and removed from the apparatus in stacks, each of which is supported by a horizontal plate 11 provided with two pairs of vertical pins 12, one pair for each stack, the pins of each pair being spaced to enter the end perforations in the blades. The plate 11 is secured to the upper end of a vertical spindle 13 rotatably mounted in a fixed bracket 14 carried by the base plate 2, with the two pairs of pins 12 symmetrically arranged on opposite sides of the vertical axis of the spindle 13 at equal distances therefrom, so that by imparting a half-rotation to the spindle and plate the two pairs of pins can be interchanged in position. This is done by means of a horizontal rack 15 which is secured to a rod 16 adapted to be moved longitudinally as hereinafter described and meshes with a segmental gear 17 formed on a sleeve 18 which surrounds and rotates with the spindle 13, being journaled in the bracket 14. The rotational movements of the spindle and plate are limited to an angle of 180° by a stop flange 19 carried by the sleeve 18 and coöperating with another stop flange 20 formed on the upper end of the bracket 14, as shown in Figs. 8 and 9, and the parts above described are so arranged that when the plate is at either limit of its rotational movements one or the other of the pairs of pins 12 is located directly behind and in line with the positioning pins 9 on the lower jaw 6 of the blade holder, as shown in Fig. 2, with the upper ends of all of said pins at substantially the same elevation.

From the supply stack carried by the pins 12, the blades are taken one by one from the top of the stack and transferred to the blade holder above described by means of a blade-transferring device which is movable horizontally in a forward and backward direction in line with and directly above the pins 9 and the pins 12 behind them, and inasmuch as the pins which receive the delivery stack of blades can be interchanged in position with the pins which carry the supply stack, the same transferring device serves also to take the finished blades from the blade holder and deposit them one by one on the delivery stack. In the particular apparatus illustrated, which is designed to operate on double-edged blades, the same transferring device is also utilized for reversing the blades edge for edge with respect to the blade holder, which is done by so constructing said device that it can be rotated through an angle of 180° on an axis perpendicular to the center of a blade carried thereby. The details of the construction employed are illustrated in Figs. 3 to 7 includ-

sive, in which 21 indicates a tube mounted to slide horizontally in a forward and backward direction in fixed brackets 22 and 23 on a frame 24 carried by the base plate 2, and 25 indicates an upright head secured to the front end of the tube 21 and provided with a vertical bearing in which is journaled a sleeve 26 surrounding a vertical spindle 27. To the lower end of the spindle 27 is attached a transverse plate 28 carrying a suction block 29 which, as shaped for use with a Gillette blade, has two annular grooves 30 extending upward from its flat bottom face and symmetrically located on opposite sides of the axis of the spindle 27, in position to surround concentrically the end perforations in the blades. These grooves 30 communicate through passages 31, Figs. 4 and 5, with a chamber 32 formed in the upper part of the block, whence a passage 33 extends upward within the spindle 27. Opposite the upper portion of the passage 33 the spindle 27 is provided externally with an annular groove 34 which communicates with said passage through a perforation 35, and opposite said groove 34 the sleeve 26 is provided with one or more perforations 36 leading to a similar annular groove 37 formed on the exterior of the sleeve, which groove 37 is in communication with the interior of the tube 21 through the open front end of the latter. At its rear end said tube 21 is provided with a nipple 38 adapted to be connected to a flexible tube through which air may be exhausted in any suitable way, the suction thus created being made effective at the bottom face of the block 29 through the communicating passages provided by the tube 21, groove 37, perforations 36, groove 34, perforation 35, passage 33, chamber 32, passages 31 and grooves 30 above described. It will be seen that these passages are so arranged that the sleeve 26 and the spindle 27 can be rotated with respect to the head 25 and the spindle 13 can be moved vertically with respect to the sleeve to a limited extent without in either case affecting the communication between the interior of the tube 21 and the annular grooves 30.

The head 25 and the parts carried thereby are moved forward and backward by a rod 39 connected to said head, and when the latter is in its rearmost position the suction block 29 is located directly over a pair of pins 12 as shown in Fig. 3, in which 40 represents a stack of blades carried by said pins. The bottom face of the block 29 is brought into contact with the topmost blade in the supply stack by a relative vertical movement of the plate 11 and said block, which is provided with vertical perforations 41 located in position to receive the corresponding pins 12 and extending upward into the head 25 far enough

to receive the full length of said pins. Thus the annular grooves 30, which are concentric with the end perforations in the blades and therefore with the pins 12 and perforations 41, are closed by the topmost blade in the stack when brought into contact therewith, so that the blade will be held against the block 29 if subjected to the suction provided for as above described.

10 The relative vertical movements of the suction block 29 and the supply stack of blades are most conveniently produced by raising and lowering the plate 11, and this is done by means of a stirrup 42 pivotally suspended on the front ends of two bell crank levers 43 and 44 fulcrumed on the bracket 14 and pivotally connected at their opposite ends to the forked front end of a longitudinally movable rod 45, with the lower end of the spindle 13 resting on the horizontal bottom portion of the stirrup 42 and connected thereto by a vertical pivot screw 46, so that the spindle can be rotated thereon. Said spindle and the sleeve 18 are connected by a spline 47 which compels them to rotate simultaneously but permits the spindle to move upward and downward independently of the sleeve, which is supported on the bracket 14 by the stop flange 19 and is held down by the rack 15 overlying said flange, the rack being prevented from moving upward by an overhanging guide 48 carried by the bracket 14.

15 The spindle 27 and suction block 29 are also arranged to move upward and downward to a slight extent in order that said block may be lowered to deposit a blade on the fixed jaw 6 of the blade holder or to pick up and remove a blade therefrom. These 20 upward and downward movements are produced by a bell crank lever 49 fulcrumed on the head 25 and operated by a rod 50 pivoted to said lever, the forked end of which is notched to receive diametrically opposite pins 51 carried by a horizontal disk 52 which is mounted on a pivot screw 53 entering the upper end of the spindle 27, so that the latter is free to rotate axially. For imparting rotational movements to said 25 spindle and the suction block 29 carried thereby I employ an arrangement similar to that used for rotating the spindle 13 and plate 11, and comprising a horizontal rack 54 secured to a longitudinally-movable rod 55 and meshing with a segmental gear 56 formed on the upper end of the sleeve 26. This sleeve is provided at its lower end with downwardly-extending portions 57, the vertical inner faces of which are in sliding 30 engagement with the flattened sides of the attaching hub 58 on the plate 28, (see Figs. 6 and 7,) whereby the rotation of said sleeve is transmitted to the spindle 27 without interfering with the relative upward and 35 downward movements of the latter. The

rotational movements of said sleeve and spindle are limited to an angle of 180° by means of coöperating stop flanges identical in construction and arrangement with the stop flanges 19 and 20 previously described, 70 the stop flange on the sleeve 26 being shown at 59 in Figs. 1 and 3.

It will be observed that the various movements of the plate 11 and the suction block 29 are imparted thereto through the agency 75 of the rods 16, 39, 45, 50 and 55 above referred to all of which extend horizontally in a forward and backward direction, this construction being adopted because it enables said parts to be operated pneumatically 80 by a series of cylinders compactly arranged in parallelism with one another and each containing a piston connected to the corresponding one of the several rods. As shown in Fig. 1, the rod 16 carries at its rear end 85 a piston 60 adapted to move longitudinally in a cylinder 61 provided with a nipple 62 leading to its interior behind the piston, through which nipple compressed air can be let into the cylinder to force the piston 90 forward. A coiled spring 63 surrounding the rod 16 within the cylinder 61 moves said piston and rod backward when the air pressure behind the piston is relieved. In like manner the rod 39 carries a piston 64 movable longitudinally in a cylinder 65, the rod 45 carries a piston 66 movable longitudinally in a cylinder 67, the rod 50 carries a piston 68 movable longitudinally in a cylinder 69 and the rod 53 carries a piston 70 movable longitudinally in a cylinder 71, all of these pistons being moved forward by the admission of compressed air through the nipples 72, 73, 74 and 75 on the rear 95 ends of the respective cylinders and being moved backward respectively by the compression springs 76, 77, 78 and 79 surrounding the corresponding rods. The cylinder 65 is carried by the bracket 23 and held in fixed position thereby, but the cylinders 69 and 71 are secured to a bracket 80 rigidly clamped on the tube 21 and therefore move with the head 25 which carries the spindle 27, so that said spindle can be rotated and moved vertically at either limit of its forward and backward travel. The cylinders 61 and 67 are rigidly secured to a fixed bracket 81 carried by the base plate 2 at one side of the frame 24. Casings 82, 83, 84, 85 and 86, carried respectively by the 100 front ends of the cylinders 61, 65, 67, 69 and 71 and constituting in effect reduced extensions thereof serve to receive the front portions of the corresponding springs 63, 76, 77, 78 and 79.

105 When the apparatus above described is in use each of the nipples 62, 72, 73, 74 and 75 is connected by a flexible tube to a suitable supply of compressed air, and provision is made for admitting the compressed 110

air to any one of the cylinders and permitting it to escape therefrom, as well as for establishing and relieving the suction in the tube 21, in such manner that the apparatus 5 operates as follows: Starting with the parts in the position shown in Fig. 1, and assuming that a supply stack of the blades to be stropped is carried by those pins 12 which are located beneath the suction block 29, the 10 plate 11 is raised until the top of the supply stack is pressed against the bottom face of said block, which at this time is held in its uppermost position by the spring 78, and thereupon the topmost blade in the stack is 15 caused to adhere to the block 29 by suction. The plate 11 is then lowered, carrying with it the remaining blades in the supply stack, and then the head 25 moves forward until the end perforations in the blade held 20 against the suction block 29 are located directly above the positioning pins 9, whereupon the block 29 moves downward and deposits the blade on the lower jaw 6 of the blade holder. The block 29 then rises and 25 the head 25 carries it back to its position above the pins 12, and at the same time the blade left on the jaw 6 is clamped in the blade holder and moved into position to be stropped. While the stropping operation 30 is going on the other parts of the apparatus remain idle, but as soon as the exposed blade edge has been stropped and the blade holder has been returned to the position shown in Fig. 2 and opened the head 25 moves forward and the blade is picked up from the lower jaw 6 by the block 29, reversed edge for edge by imparting a half rotation to the spindle 27 and again deposited on the jaw 6, whereupon the head 25, spindle 27 and block 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

stack of blades are located at one side of the blade-transferring mechanism, where the stack is conveniently accessible for removal from time to time by the attendant, who also replenishes the supply stack from time 70 to time in the intervals during which this stack is interchanged in position with the delivery stack. Thus the continuous operation of the apparatus is not interfered with by the introduction of the blades to be 75 stropped or the removal of the stropped blades.

The blade-transferring mechanism above described can be operated otherwise than pneumatically if desired, but pneumatic operation is preferable for various reasons, among which may be mentioned the facility in which the power for operating the spindle 27 is applied thereto through flexible connections in any position of the head 25, 85 and the possibility of operating a large number of identical machines simultaneously by employing common sources of compressed air and of suction for all of them, with a single control for regulating the admission 90 and release of the compressed air pressure and for establishing and relieving the suction for all the machines. Pneumatic operation is also advantageous in the case of parts which have an indeterminate movement, such as the plate 11 for example, which is moved upward until the topmost blade in the supply stack is pressed against the suction block 29, whatever the height of the stack may be at any given time. The 100 air pressure which produces this movement also forces said blade into such close contact with the block 29 as to insure its retention by the block when the suction is exerted, and the same result is secured in like manner when the block 29 moves downward to pick up a blade from the lower jaw 6 of the blade holder. When said block 29 is lowered to place a stropped blade on the pins 12 its downward movement is limited 110 by the engagement of a stop finger 87 on the lever 49 with the bracket which supports said lever, but it will be obvious that the stropped blades can be placed on the pins 12 by elevating the plate 11 instead of lowering the block 29, if preferred.

The forward movement of the head 25 is positively arrested by the engagement of a collar 88 clamped on the tube 21 with the rear face of the fixed bracket 22, and its 120 rearward movement is arrested by the simultaneous engagement of said head and the bracket 80 with the front faces of the brackets 22 and 23, washers 89 being preferably interposed between the engaging parts. 125 When the head 25 is at the limit of its forward movement the suction block 29 is properly positioned above the lower jaw 6 of the blade holder, and in order to prevent shock such as might cause a blade carried by the 130

block 29 to be disengaged therefrom when the collar 88 brings up against the bracket 22 I employ a checking device such as is shown in detail in Fig. 3, in which 90 indicates a nipple entering the otherwise closed front end of the casing 83 and carrying a ball valve 91 so arranged that air is freely admitted through the nipple when the piston 64 moves backward but is compressed in front of the piston when the latter is forced forward by the admission of compressed air behind it. The air thus compressed in front of the piston passes slowly out of the casing 83 through a small perforation 92, so that it checks the forward movement of the piston without preventing its ultimate completion.

It will be evident that my apparatus may be readily adapted to handle various blades other than Gillette blades, in which case the blade-positioning devices employed will be constructed and arranged in such manner as to accommodate the particular style of blade to be handled, and that if such blades are single-edged the provision of means for reversing them edge for edge will be unnecessary. It will also be evident that the blade-transferring mechanism may be used in various machines other than blade-stropping machines and may be employed to carry blades to and from any form of blade holder or equivalent device adapted to receive the blades one by one, and that the construction of this mechanism and of the blade stack support and its operating devices may be widely modified without departing from my invention.

I claim:

1. In a blade-handling apparatus, the combination of a blade support having means for positioning supply and delivery stacks of blades thereon, and means for moving the support laterally to bring each stack in alternation into the position previously occupied by the other.

2. In a blade-handling apparatus, the combination of a blade support having means for positioning supply and delivery stacks of blades thereon, means for moving the support laterally to bring each stack in alternation into the position previously occupied by the other, and means for raising and lowering the support.

3. In a blade-handling apparatus, the combination of a blade support mounted to rotate on a vertical axis and provided with means for positioning supply and delivery stacks of blades thereon at equal distances from and on opposite sides of its axis of rotation, and means for rotating said support to interchange the positions of the stacks.

4. In a blade-handling apparatus, the combination of a blade support provided with pairs of upwardly-extending positioning pins, and means for moving the support laterally to bring either pair of pins into a

position previously occupied by the other pair.

5. In a blade-handling apparatus, the combination of a blade support mounted to rotate on a vertical axis and provided with two pairs of upwardly-extending positioning pins located at equal distances from its axis of rotation, means for rotating said support, and means for raising and lowering it.

6. In a blade-handling apparatus, a blade-reversing device comprising means for engaging and retaining a blade, and means for imparting a half-rotation thereto on an axis perpendicular to the plane of the blade and passing through the center of the latter.

7. In a blade-handling apparatus, a blade-reversing device comprising a vertical spindle carrying a downwardly-facing suction block at its lower end, and means for rotating the spindle on its vertical axis.

8. In a blade-handling apparatus, a blade-transferring device comprising a laterally-movable head, a spindle movable vertically therein and carrying a downwardly-facing suction block at its lower end, and means for raising and lowering the spindle.

9. In a blade-handling apparatus, a blade-transferring device comprising a laterally-movable head, a rotatable spindle movable vertically therein and carrying a downwardly-facing suction block at its lower end, means for rotating the spindle, and means for raising and lowering it.

10. In a blade-handling apparatus, a blade-transferring device comprising a laterally-movable head, a vertical sleeve journaled therein, a spindle movable vertically in the sleeve and carrying a downwardly-facing suction block at its lower end, means for raising and lowering the spindle, and means for rotating the sleeve and spindle.

11. In a blade-handling apparatus, a blade-transferring device comprising a laterally-movable head, a spindle movable vertically therein and provided at its lower end with means for engaging a blade and holding it in a horizontal plane, and means movable with the head for raising and lowering the spindle.

12. In a blade-handling apparatus, a blade-transferring device comprising a laterally-movable head, a rotatable spindle movable vertically therein and provided at its lower end with means for engaging a blade and holding it in a horizontal plane, and means movable with the head for rotating the spindle and for raising and lowering it.

13. In a blade-handling apparatus, the combination of a blade support having means for positioning supply and delivery stack of blades thereon, a blade-transferring device movable laterally above the support and including means for taking single blades from the supply stack and for de-

positing single blades on the delivery stack, and means for moving the blade support laterally to bring either stack beneath the blade-transferring device.

- 5 14. In a blade-handling apparatus, the combination of a blade support having means for positioning supply and delivery stacks of blades thereon, a blade-transferring device including a downwardly-facing suction block movable laterally above the support, means for raising and lowering said support, and means for moving it laterally to bring either stack beneath the suction block.
- 10 15. In a blade-handling apparatus, the combination of a blade support having two pairs of upwardly-extending positioning pins thereon, a blade-transferring device including a downwardly-facing suction block movable laterally above the support, means for raising and lowering said support, and means for moving it laterally to bring either pair of positioning pins beneath the suction block, the latter being provided with upwardly-extending recesses to receive said pins.

16. In a blade-handling apparatus, the combination of a blade support having two pairs of upwardly-extending positioning pins thereon, a blade-transferring device including a downwardly-facing suction block movable laterally above the support, means for raising and lowering said support, means for moving it laterally to bring either pair of pins beneath the suction block, the latter being provided with upwardly-extending recesses to receive said pins, and means for raising and lowering the suction block.

17. In a blade-handling apparatus, the combination of a blade-clamping device having a horizontal lower jaw and means for positioning a blade thereon, a blade-transferring device movable laterally above said jaw and including a suction block adapted to retain a blade placed against its bottom face, and means for raising and lowering the suction block.

18. In a blade-handling apparatus, the combination of a blade-clamping device having a horizontal lower jaw with upwardly-extending positioning pins thereon, a blade-transferring device movable laterally above said jaw and including a suction block adapted to retain a blade placed against its bottom face and having recesses to receive said positioning pins, and means for raising and lowering the suction block.

19. In a blade-handling apparatus, the combination of a blade-clamping device having a horizontal lower jaw with upwardly-extending positioning pins thereon, a blade-transferring device movable laterally above said jaw and including a suction block adapted to retain a blade placed against its bottom face and having recesses to receive

said positioning pins, means for raising and lowering the suction block and means for rotating said block on a vertical axis passed through the center of a blade carried thereby.

20. In a blade-handling apparatus, the combination of a blade support having means for positioning a supply stack of blades thereon, a blade holder having means for positioning single blades thereon, a blade-transferring device movable laterally above the blade support and blade holder and having means for taking a blade from either, and means for bringing the transferring device into engagement with a blade beneath it.

21. In a blade-handling apparatus, the combination of a blade support having means for positioning a supply stack of blades thereon, a blade holder having means for positioning single blades thereon, a blade-transferring device including a suction block movable laterally above the blade support and blade holder and adapted to retain a blade on its bottom face, and means for bringing the suction block into contact with a blade on the blade holder or on the top of the supply stack.

22. In a blade-handling apparatus, the combination of a blade support having means for positioning supply and delivery stacks of blades thereon, a blade holder having means for positioning single blades thereon, a blade-transferring device movable laterally above the blade support and blade holder and having means for taking a blade from either, means for bringing the transferring device into engagement with a blade beneath it, and means for presenting either the supply stack or the delivery stack beneath the blade-transferring device.

23. In a blade-handling apparatus, the combination of a blade support having means for positioning supply and delivery stacks of blades thereon, a blade holder having means for positioning single blades thereon, a blade-transferring device including a suction block movable laterally above the blade support and blade holder and adapted to retain a blade on its bottom face, means for raising and lowering the blade support and the suction block, and means for presenting either the supply stack or the delivery stack beneath the suction block.

24. In a blade-handling apparatus, the combination of a blade support having means for positioning supply and delivery stacks of blades thereon, a blade holder having means for positioning single blades thereon, a blade-transferring device including a suction block movable laterally above the blade support and blade holder and adapted to retain a blade on its bottom face, means for raising and lowering the blade support and the suction block, means for presenting either the supply stack or the

delivery stack beneath the suction block, and means for rotating said block on a vertical axis passing through the center of a blade carried thereby.

5. 25. In a blade-handling apparatus, the combination of a blade support having a pair of upwardly-extending positioning pins thereon, a blade holder having a horizontal portion provided with upwardly extending 10 positioning pins spaced in correspondence with the pins on the blade support, a blade-transferring device including a suction block movable laterally above the blade support and the horizontal portion of the blade holder 15 and adapted to retain a blade on its bottom face, said suction block being provided with recesses to receive said pins, means for raising and lowering the blade support, and means for independently raising and lowering the 20 suction block.

26. In a blade-handling apparatus, the combination of a blade support having a pair of upwardly-extending positioning pins thereon, a blade holder having a horizontal 25 portion provided with upwardly-extending positioning pins spaced in correspondence with the pins on the blade support, a blade-transferring device including a suction block movable laterally above the blade support and the horizontal portion of the blade 30 holder and adapted to retain a blade on its bottom face, said suction block being provided with recesses to receive said pins, means for raising and lowering the stack 35 support, means for independently raising and lowering the suction block, and means for rotating the suction block on a vertical axis.

27. In a blade-handling apparatus, the 40 combination of a blade support having two pairs of upwardly-extending positioning pins thereon, a blade holder having a horizontal portion provided with a pair of upwardly-extending positioning pins spaced in 45 correspondence with the pins on the blade support, a blade-transferring device including a suction block movable laterally above the blade support and the horizontal portion of the blade holder and adapted to retain a 50 blade on its bottom face, said block being provided with recesses to receive either pair of said pins, means for raising and lowering the blade support and the suction block, and means for moving the blade support laterally to bring either pair of its positioning 55 pins beneath the suction block.

28. In a blade-handling apparatus, the combination of a blade support having two pairs of upwardly-extending positioning pins thereon, a blade holder having a horizontal portion provided with a pair of upwardly-extending positioning pins spaced in correspondence with the pins on the blade support, a blade-transferring device including a suction block movable laterally above

the blade support and the horizontal portion of the blade holder and adapted to retain a blade on its bottom face, said block being provided with recesses to receive either pair of said pins, means for raising and lowering the blade support and the suction block, means for moving the blade support laterally to bring either pair of its positioning pins beneath the suction block, and means for rotating the suction block on a vertical axis passing through the center of a blade carried thereby.

29. In a blade-handling apparatus, the combination of a blade support, a blade holder, a blade-transferring device movable from one to the other and including means for taking a blade from either, and means for operating the blade-transferring device comprising a cylinder with a piston therein and connections between the piston and blade-transferring device.

30. In a blade-handling apparatus, the combination of a laterally-movable head, a downwardly-facing suction block carried thereby, means for operating the head comprising a pneumatic cylinder with a piston therein and connections between the piston and head, a stop for positively limiting the movement of the head, and a checking device for retarding such movement.

31. In a blade-handling apparatus, the combination of a laterally-movable head, an upright spindle carried thereby and provided at its lower end with means for engaging and retaining a blade, and pneumatically-operated means movable with the head for moving the spindle vertically.

32. In a blade-handling apparatus, the combination of a laterally-movable head, an upright rotatable spindle carried thereby and provided at its lower end with means for engaging a blade and holding it in a horizontal plane, and pneumatically-operated means movable with the head for imparting vertical and rotational movements to the spindle.

33. In a blade-handling apparatus, the combination of a laterally-movable head, an upright spindle carried thereby and provided at its lower end with a downwardly-facing suction block, pneumatically-operated means for moving the head laterally, and pneumatically-operated means movable with the head for imparting vertical movements to the spindle.

34. In a blade-handling apparatus, the combination of a laterally-movable head, a rotatable upright spindle carried thereby and provided at its lower end with a downwardly-facing suction block, pneumatically-operated means for moving the head laterally, and pneumatically-operated means movable with the head for imparting independent vertical and rotational movements to the spindle.

35. In a blade-handling apparatus, the combination of a blade support having means for positioning a supply stack of blades thereon, a blade-transferring device located above the support, and pneumatically-operated means for lifting the support to bring the topmost blade in the stack into engagement with the transferring device.

36. In a blade-handling apparatus, the combination of a rotatable and vertically-movable blade support having means for positioning supply and delivery stacks of blades thereon, a laterally-movable blade-transferring device located above the support and provided with means for taking blades one by one from the top of the supply stack, and means for operating the blade support and blade-transferring device comprising a series of pneumatic cylinders each containing a piston connected to the part to be operated thereby.

37. In a blade-handling apparatus, the combination of a rotatable and vertically-movable blade support having means for positioning supply and delivery stacks of blades thereon, a laterally-movable blade-transferring device located above the support and including a vertically movable spindle provided at its lower end with means for taking blades one by one from the top of the supply stack, and means for operating the blade support, blade-transferring de-

vice and spindle comprising a series of pneumatic cylinders each containing a piston connected to the part to be operated thereby, the cylinder for operating the spindle being movable laterally with the blade-transferring device.

38. In a blade-handling apparatus, the combination of a fixed support, a horizontal tube arranged to slide longitudinally therein, an upright head carried by said tube, a spindle movable vertically therein, a suction block carried by the lower end of the spindle and provided with suction spaces in communication with the interior of the tube, and pneumatically-operated means carried by said tube for imparting vertical movements to the spindle.

39. In a blade-handling apparatus, the combination of a fixed support, a horizontal tube arranged to slide longitudinally therein, an upright head carried by said tube, a rotatable spindle movable vertically therein, a suction block carried by the lower end of the spindle and provided with suction spaces in communication with the interior of the tube, and pneumatically-operated means carried by said tube for imparting independent vertical and rotational movements to the spindle.

Signed at Boston, Mass., this 19th day of May, 1916.

WILLIAM E. NICKERSON.
